UNITED STATES PATENT OFFICE.

CARL STIELER, OF CHICAGO, ILLINOIS.

MOLD FOR TAPERING-CHIMNEY CONSTRUCTION.

No. 890,466.

Specification of Letters Patent.

Patented June 9, 1908.

Application filed July 1, 1907. Serial No. 381,729.

To all whom it may concern:

Be it known that I, CARL STIELER, a citizen of the United States, and residing at Chicago, in the county of Cook and State of Illinois, have invented a new and useful Improvement in Molds for Tapering-Chimney Constructions, of which the following is a complete specification.

This invention relates to molds for tapering chimney constructions, and more particularly to an adjustable mold by means of which the thickness as well as the diameter of the chimney may be regulated within certain limits.

15 The object of this invention is to provide a mold for concrete chimney constructions which is adapted to be adjusted by removing or inserting segments thereof, so as to vary the diameter of the chimney to meet the requirements of the construction.

20 It is a further object of the invention to provide a simple construction adapted to be readily set up or knocked down for filling and for removing from the completed section of 25 the chimney.

Another object of the invention is to provide a mold, which while it is collapsible, affords when assembled a very rigid construction capable of holding its shape under the 30 strain caused in operation.

The invention consists of the matters hereinafter described in the specification and more fully pointed out and defined in the appended claims.

35 In the drawings: Figure 1 is a view partly in elevation and partly in section, with parts removed, of a device embodying my invention. Fig. 2 is a fragmentary, top plan view of the same with parts removed. Fig. 3 is a 40 fragmentary view of the shells showing one half thereof in elevation and the other half in vertical section. Fig. 4 is a fragmentary, top plan view thereof. Fig. 5 is a view partly in elevation and partly in section of 45 the supporting frame for the shells. Fig. 6 is a fragmentary, top plan view thereof. Fig. 7 is an end view of one of the air space forms. Fig. 8 is a section taken on line A—A of Fig. 7. Fig. 9 is an enlarged partial section taken on any of the lines B—B of Fig. 2. Fig. 10 is an enlarged section taken on line C—C of Fig. 2. Fig. 11 is a plan view of one of the segment sections of the mold, and Fig. 12 is a fragmentary elevation of the same.

55 As shown in said drawings: a supporting frame is provided in which the mold is sup-

ported and which may be of any preferred construction and material but, which as shown, comprises a pair of upper and a pair of lower concentric rings of channel iron or other suitable material and indicated respectively by 1—1' and 1²—1³. Connecting the two outer rings and the two inner rings of said pairs are the uprights 2, which may likewise be of channel iron if preferred, and the outer ones of which are rigidly bolted to the outer side of the rings 1 and 1² and the inner ones to the inner sides of the rings 1' and 1³, as shown more clearly in Figs. 2, 5 and 6. The upper ends 2' of said uprights 2 are bent 60 transversely and across the rings to which they are attached and are slotted longitudinally as is shown in Figs. 2 and 6. Corresponding upper and lower rings may be of the same size if preferred but as shown the 65 upper ones are of less diameter than the lower ones and a block 2² of wood or other preferred material is inserted between the flanges of each ring, and the uprights are bolted therethrough and through the rings. The 70 molds are adjustably supported between the outer and inner rings of said frame and comprise an outer and an inner shell 3 and 3', each constructed of tapered segments extending longitudinally thereof, and which, if 75 preferred, though not shown, may be constructed of varying widths, so that the shells may be increased or decreased in diameter in varying degrees by inserting or removing a segment or segments of the desired sizes. 80 Each of said segments comprises a transversely curved plate of sheet metal 3², having on its outer side an upper, lower and central pair of slide rails indicated respectively by 85 3³, 3⁴ and 3⁵. Each of said rails comprises a 90 bar rigidly engaged by bolting or riveting to the plate, transversely thereof, and having on its outer edge a longitudinal flange turned towards the other bar of the same pair, thereby forming a slot opening into a channel 95 beneath said flanges. A connecting rod or bar 3⁶ extends longitudinally of each plate on the outer side thereof and is rigidly engaged to said rails 3⁴ by means of a bolt 3⁷ extending therethrough and having its head engaged beneath the flanges of the rails as shown 100 more clearly in Fig. 1. The ends of said connecting rods or bars of the outer shell are engaged to the upper and lower pairs of rails by the adjusting bolts 4 and 4' respectively, and 105 those of the inner shell are engaged to the upper and lower pairs of rails thereof by the ad- 110

justing bolts 5 and 5'. Inasmuch as all of said bolts are of like construction a description of one will suffice. A threaded socket 6 is provided for each bolt and has a bracket 6' thereon which is pivotally engaged to one of the rings of the supporting frame, thereby allowing the socket to swing about its pivot as an axis. The bolt, as 4, has threaded engagement in the socket and the head 4' thereof is inserted between the adjacent pair of rails, as 3², where it engages beneath the flanges of said rails. Said bolt is provided with a collar 4³, which may be engaged on the bolt in any preferred manner in close contact with the rod or bar 3⁶, so that as the bolt is turned in its socket it acts to move the shell or the segment if the segments are not connected together. As shown, joint plates 7 overlap the joints between the segments, on the outer sides thereof, and are bolted to the plates 3², thereby firmly connecting them together. Said shells are further supported by means of hangers 8 which are adjustably engaged in the slotted ends 2' of the uprights 2 and have their lower ends bent at right angles and provided with a head 8' adapted to engage between the upper rails 3².

The operation is as follows: The supporting frame is set up and segments of the proper widths to form shells of the desired circumference are mounted thereon by means of the adjusting screws and their sockets and the hangers 8. Said bolts are then turned to bring the segments into proper position where they are secured together by the joint plates 7. The concrete 9 or other plastic material is then poured between the shells and allowed to set, when the mold may be removed by removing the segments separately or by simply removing one segment from each shell and then drawing the remaining portion of the shell out of contact with the concrete by means of the adjusting screws, when it may be lifted away.

If preferred, and as shown, air spaces may be left in the concrete and for this purpose a collapsible form comprising U shaped sections 10 and 10' is provided. The flanges of said sections overlap and are bolted together as shown in Fig. 7, and a wedge 10² of wood or other preferred material is inserted in the shell to hold it in shape.

Obviously the diameter of the shells may be varied by inserting or removing segments, and by varying the taper of the segments the taper of the chimney will be varied. Obviously also various details of construction may be varied without departing from the principles of my invention.

I claim as my invention:

1. In a device of the class described, the combination with a supporting frame comprising inner and outer members, adjusting bolts pivotally engaged on each member, an inner and an outer shell supported on said

bolts, and hangers on said members adapted to engage said shells at the tops.

2. In a device of the class described, the combination with a supporting frame, of an inner and an outer shell thereon, comprising segments, and means adjustably supporting the segments of each shell on the frame.

3. In a device of the class described, the combination with an outer and an inner frame member, of threaded sockets pivotally engaged on said members, adjusting bolts in said sockets, an inner and an outer shell engaged at their sides on said bolts, and radially adjustable hangers on said members adapted to support the shells from their tops.

4. In a device of the class described, the combination with a supporting frame of a plurality of upwardly tapering segmental sections thereon, and an adjusting bolt for each segment pivotally supported on said frame adapted to adjust said sections with respect to each other.

5. In a device of the class described, the combination with a supporting frame comprising an inner and an outer member, of adjusting bolts pivotally engaged on each member, a segmental shell carried on the bolts of each member, and adjustable hangers on said members adapted to support the shells from their tops.

6. In a device of the class described, the combination with an inner and an outer supporting frame member, of a plurality of adjustable supports pivotally engaged thereon, a plurality of segment sections carried on said supports, and means for engaging said sections together and forming an outer and an inner shell.

7. In a device of the class described, the combination with a supporting frame of an inner and an outer shell, adjusting bolts pivotally engaged on said frame and supporting said shells at their sides, and hangers carried on said frame and supporting said shells from the top.

8. In a mold of the class described, the combination with a pair of outer and a pair of inner rings, of uprights connecting the rings of each pair together, a plurality of adjusting bolts pivotally engaged on each ring, a plurality of segment sections, slide rails on each section adapted to engage the sections to said bolts, means for engaging said sections together, and hangers adjustably engaged to said uprights and said upper slide rails.

9. In a device of the class described, the combination with a plurality of upper and lower rings, of uprights thereon having their upper ends bent laterally and slotted, sockets pivoted on said rings, adjusting bolts therein, an inner and an outer set of segments engaged on said bolts and arranged concentrically, means for engaging the segments of each set together, and hangers adjustably engaged on

the upper ends of said uprights and adapted to support said sets from the top:

10. In a device of the class described, the combination with a supporting frame of a plurality of outer and inner adjusting bolts pivotally engaged thereon near the top and bottom thereof, a plurality of segments, each having an upper and a lower pair of slide rails thereon adapted to engage said bolts, a 10 bar connecting said rails, joint plates adapted to engage said segments together, and hangers adjustably engaged on said frame and on the upper slide rails.

11. In a device of the class described, the 15 combination with an outer and an inner frame member, of a plurality of threaded sockets pivoted at the top and bottom thereof, a bolt having threaded engagement in each socket, a plurality of segment sections, and 20 slide rails thereon adapted to engage said bolts.

12. In a device of the class described, the combination with an outer and an inner circular frame, of upper and lower adjusting 25 bolts pivotally engaged thereon, and an outer and an inner shell each comprising a plurality of segments detachably engaged to said bolts.

13. In a device of the class described, the combination with an upper and a lower pair 30 of frame rings, of uprights connecting corresponding upper and lower rings and having inturned upper ends, a hanger adjustably

engaged on each of said ends, sectional shells suspended on said hangers, and adjustable supports for each shell pivotally engaged on 35 said rings.

14. In a device of the class described, the combination with a supporting frame of an inner and an outer shell, hangers suspended on said frame and adapted to support said 40 shells at their tops, upper, lower and intermediate slide rails on said shells, connecting bars connecting said rails, and outer and inner adjusting bolts pivotally engaged on said frame and adapted to support said shells at 45 their sides.

15. In a device of the class described, the combination with a supporting frame of a plurality of threaded sockets pivotally engaged adjacent the top and bottom thereof, 50 adjusting bolts engaged in said sockets and each having a collar and a head on its inner end, a plurality of segment sections, upper and lower pairs of slide rails on each section adapted to engage over the heads of said 55 bolts, and connecting bars connecting corresponding upper and lower bolts.

In testimony whereof I have hereunto subscribed my name in the presence of two witnesses.

CARL STIELER.
